UNITED STATES PATENT OFFICE.

CARL J. IPSEN, OF JAMESTOWN, NEW YORK.

WRENCH.

1,182,567.

Specification of Letters Patent.

Patented May 9, 1916.

Application filed October 23, 1915. Serial No. 57,521.

To all whom it may concern:

Be it known that I, CARL J. IPSEN, a citizen of the United States, residing at Jamestown, in the county of Chautauqua and State of New York, have invented new and useful Improvements in Wrenches, of which the following is a specification.

The present invention relates to wrenches primarily adapted for use upon pipes or tubes, the object being to provide a wrench of this class wherein one of the jaws will be normally sustained at an angle to the second jaw to provide a flaring mouth for the reception of the tube or pipe, and further wherein the wrench may be instantly adjusted for receiving pipes and tubes of varying diameters.

A still further object of the invention is to construct a wrench of this class which shall embody, in principle only two members, each being provided with a jaw, one of the members being substantially U-shaped in cross section and the jaw or engaging portion thereof being arranged at an angle above the rear wall or connecting member for the sides, and to provide the said jaw portion with a filler block which shall embody a number of engaging faces, any of which may be brought into surface.

With the above and other objects in view, the improvement resides in the construction, combination and operative arrangement of parts set forth in the following specification and falling within the scope of the appended claim.

In the drawing: Figure 1 is an elevation of a wrench constructed in accordance with the present invention, parts being broken away and parts being shown in section and illustrating one of the jaws swung angularly of the second jaw, Fig. 2 is a similar view but illustrating the shanks of the wrench in alinement, and Fig. 3 is a perspective view of the toothed filler member for one of the sections of the wrench.

Referring now to the drawings in detail, the numeral 1 designates a substantially rectangular member which comprises the shank of one of the jaws of my improved wrench. This member has one of its ends offset to provide the jaw proper, the same being indicated by the numeral 2, and the inner and working face of the jaw is provided with teeth 3. The shank upon its

edge formed with the jaw 2 is provided at 55 spaced intervals with a plurality of angularly disposed notches 4, the same terminating in rounded walls 5. The free end of the shank 1 may and preferably does have its sides beveled and its edges rounded toward its ends to provide an implement for engaging with the slots in the heads of screws, or for other similar purposes.

The numeral 6 designates the second member or leg of the wrench. This member, for 65 the major portion of its length, is U-shaped in cross section, providing spaced sides 7 and a connecting member 8. The sides 7 are spaced a sufficient distance to receive therebetween the shank 1, and the said sides, 70 above their connecting wall 8, are rounded outwardly, as at 9, and adapted to be removably secured between the said rounded portions 9 is a block 10, the said block being substantially V-shaped to conform to the 75 shape of the edges of the said portions 9 and each of its faces is formed with teeth 11. The jaw 2 extends a sufficient distance from the shank 1 to project beyond the portions 9 of the leg 6 when the legs are swung together, as shown in Fig. 2 of the drawings, and the side members 6 below the block 10 have a connecting or pivot member 12 which is adapted to be received within one of the notches 4 of the shank 1.

The shank 1 is of a width greatly less than the distance between the terminal of the wall 8 and the inner face of the block 10, so that the same may be moved inwardly or toward the said wall 8 and brought out 90 of engagement with the stud 12 when desired, and so the jaw 2 may be easily and quickly adjusted upon the leg 6 of the wrench, and the jaws brought to the proper or desired spaced relation.

The wall 8 of the leg 6 is provided with an opening or slot 13 within which is received the offset end 14 upon one of the legs 15 of a two-leaf spring, the second leaf 16 engaging with the inner edge of the 100 shank or leg 1 at a suitable distance below the pivot pin 12, and as a consequence, leg 1 is at all times retained at an angle with relation to the leg 6.

From the above description, taken in connection with the accompanying drawing, the simplicity of the device, as well as the advantages thereof will, it is thought, be

perfectly apparent to those skilled in the art to which such invention appertains without further detailed description.

Having thus described the invention, what I claim is:

A wrench comprising a shank having an outer jaw thereon, said shank being provided with a plurality of gaps therein, a second shank which is U-shaped in cross section, the upper ends of the parallel portions thereof extending beyond the connected portion thereof to provide rounded portions, a jaw secured between said rounded portions, said first mentioned shank lying between said parallel portions, a pivot pass-

ing through both of the parallel portions at a point below the upper edge of the said connecting portion, said pivot engaging any one of the gaps in the first shank, and a spring secured in the U-shaped shank and 20 engaging with the first mentioned shank, the upper edge of the said connecting portion forming an abutment for the first shank and limiting the rearward movement thereof.

In testimony whereof I affix my signature in presence of two witnesses.

CARL J. IPSEN.
